SPACER FOR CONCRETE REINFORCING RODS

Joseph Patrick Toner, 117 Rathmore Drive, Rathcoole,
Newtownabbey, County Antrim, Northern Ireland

Filed Mar. 23, 1973, Ser. No. 344,109

Term of patent 14 years

Int. Cl. D8—08

U.S. Cl. D8—228

FIG. 1.

FIG. 2.

FIG. 4

FIG. 5

FIG. 1 is a perspective view of the spacer for concrete reinforcing rods, the view from the side opposite being substantially similar, and

FIG. 2 is a plan top view.

I claim:

The ornamental design for a spacer for concrete reinforcing rods, substantially as shown and described.
